UNITED STATES PATENT OFFICE.

JAMES H. PEIRCE, OF BLOUNTSVILLE, INDIANA, ASSIGNOR OF ONE-HALF OF HIS RIGHT TO JONATHAN ROSS, OF SAME PLACE.

CULTIVATOR.

SPECIFICATION forming part of Letters Patent No. 227,383, dated May 11, 1880.

Application filed February 9, 1880.

To all whom it may concern:

Be it known that I, JAMES H. PEIRCE, of the town of Blountsville, county of Henry, and State of Indiana, have invented certain new and useful Improvements in Cultivators, of which the following is a specification, reference being had to the accompanying drawings, which are made a part hereof, and on which similar letters of reference indicate similar parts.

Figure 1 is a top or plan view of an implement embodying my improvements in position as when the wheel-spindles are in line with each other. Fig. 2 is a similar view in position as when one wheel is in advance of the other. Fig. 3 is a rear elevation as seen from the dotted line $z z$, the plows not being shown. Fig. 4 is a longitudinal vertical section on the dotted line $x x$.

20 In said drawings the portions marked A represent the wheels of the plow; B, frames constructed to meet the requirements of my invention, attached to and supported by the wheel-spindles; C, draft-rods constructed in 25 the form of a light frame-work and attached by pivots e to the frames B; D, an arch connecting the two frames B; E, hounds reaching forward from the frames B to form a connection for the tongue; F, a tongue, which is connected at the proper point by the pivot f to the point of the hounds E, and the rear end of 30 which passes between the cross-bars E', thus providing for free lateral movement, and G the plows.

35 The object of my invention is, first, to produce a corn-plow in which the vertical movement of the wheels in passing over obstructions or into ruts shall not operate to materially disturb the plow itself or cause it to run 40 unevenly in the ground; second, to attach the plow directly to the draft-bars, and not to the side frames; third, to so construct the frames, arch, and tongue that the wheels and plows may pass and repass each other in the 45 direction of their progression, as indicated in Figs. 1 and 2, without throwing the front end of the tongue from side to side; and, fourth,

to allow such relative changes of the position of the parts to take place without subjecting any of them to any unusual strain.

50 The first and second of these objects I attain by attaching to the frames B, at a point to the rear of the wheel-spindles, a light frame-work, C, or a suitable draft-bar, by means of pivots e , and attaching the points of the plow-beams 55 to a cross-rod, C', which forms part of the frame-work C, and is preferably about midway between the point of draft attachment and the wheel-spindles. This arrangement admits of the wheels rising and falling a considerable distance without materially affecting the position of the point of the plow-beams or the plows attached thereto.

60 The third and fourth objects I attain by attaching the arch D to the frames B in such a manner that the latter will pivot freely on the former, and by pivoting the tongue F to the point of the hounds E in such a manner that while it is horizontally rigid therewith the lateral relative position will freely change as 65 the point of the tongue is moved sidewise or the wheels advance and recede relatively to each other.

70 By changing the downwardly-projecting parts of the arch D from one set to another of 75 the holes $d d$ in the top portion of the frames B B the distance between said frames can be varied to suit the width of rows, and the distance between the plows can be varied, so as to plow closer or farther from the corn, by 80 moving the point of attachment on the bars C'.

Having thus fully described my said invention, what I claim as new, and desire to secure by Letters Patent, is—

1. In a corn-plow, the draft bar or frame C, 85 loosely pivoted to the side frames, B, by the horizontal pivots e , to a point to the rear of the wheel-spindles, and having the point of power attachment in front thereof, while the plows are attached to said bar or frame at an 90 intermediate point, all substantially as shown and described, and for the purposes specified.

2. In a corn-plow, the wheels A, frames B, arch D, hounds E, tongue F, loosely-pivoted

bars or frames C, and plows G, all arranged and operating in combination with each other, substantially as shown and specified.

3. In combination with the side frames of a 5 corn - plow loosely pivoted on the arch and having the draft bars or frames loosely pivoted thereto, a tongue pivoted in the manner shown, said several parts being thus constructed to allow each of them to occupy vary-

ing relations to the others, all substantially as 10 shown and set forth.

In witness whereof I have hereunto set my hand and seal at Blountsville, Indiana, this 2d day of February, A. D. 1880.

JAMES H. PEIRCE. [L. S.]

In presence of—

GEORGE W. SMELTZER,
LEWIS W. DAY.
